UNITED STATES PATENT OFFICE

MARSHALL F. SMITH, OF LOWELL, MASSACHUSETTS, ASSIGNOR TO EDDO V. BATES, OF LOWELL, MASSACHUSETTS.

STEAM HEATING APPARATUS.

No. 902,539.

Specification of Letters Patent. Patented Oct. 27, 1908.

Application filed June 11, 1903. Serial No. 161,033.

To all whom it may concern:

Be it known that I, MARSHALL F. SMITH, a citizen of the United States, and residing in Lowell, in the county of Middlesex and Commonwealth of Massachusetts, have invented a certain new and useful Improvement in Steam Heating Apparatus, of which the following is a specification.

This invention relates to steam heating apparatus and its principal object is to secure a more perfect and uniform circulation of steam throughout the entire system of pipes and radiators and thereby to effect a saving of fuel.

This invention is applicable to apparatus in which steam is used at a low pressure or at a high pressure, and while a part of said invention serves a useful purpose in "one-pipe" systems, that is, systems in which the supply-pipe is used to return the water of condensation to the boiler, the best results are attained by the use of the entire invention in systems having a separate return-pipe for each radiator.

Said invention consists in the devices and combinations hereinafter described and claimed.

In the accompanying drawing on three sheets, Figure 1 represents a steam heating apparatus embodying my invention, showing the main system of pipes and radiators in front elevation and a branch system in end elevation; Fig. 2, a front elevation of the branch system showing its connection with the main system; Fig. 3, a side elevation of the condensation-receiver and connected parts.

The boiler A, doors a^1 a^2 a^3 , smoke-pipe C, the diaphragm D and connection with the ash-pit door a^3 to regulate the draft and the radiators G G^1 G^2 are or may be all of any usual construction.

In this apparatus the main supply-pipe H (Figs. 1 and 2) after rising vertically at h from the steam-space of the boiler A, descends by a slight inclination to the radiator-connection or feed-riser g, farthest from the boiler. The main drip-pipe I is connected to the end of the supply-pipe H at the feed-riser g by the pipe h^1 which is the beginning of the drip-pipe and said pipe I is thence inclined downward and back to a stand-pipe i, the lower end of which enters the boiler below the water-line, said stand-pipe i also

forming a portion of the drip-pipe. The 55 drip-pipe I enters the stand-pipe i above the water-line of the boiler and said stand-pipe i rises above the highest point of the drip-pipe to form an air-chamber i¹, the upper end of which is provided with an automatic 60 air-valve i² of any approved construction arranged to discharge above the lower end of the main supply pipe. This arrangement permits any air in the supply-pipe and the 65 condensation water therein to be disposed of before they reach the radiators, the water running through the supply-pipe and drip-pipe to the boiler and the air passing out through the air-chamber i¹ and automatic 70 air-valve i², the air in the main or supply pipe being forced by the pressure of the steam beyond the lower end of the riser farthest from the boiler and being carried, partly by the friction of the condensed water, to the stand-pipe through the smaller inclined drip-pipe and rising in the stand-pipe, while the 75 water descends in said stand-pipe, the air passing out of said valve.

The steam enters the radiators G G^1 from the supply-pipe through feed-risers g g^1 in 80 the usual manner, expelling the air from said radiators through automatic air-valves g^3 g^4 and the water of condensation descends in the return-risers g^6 g^7 to the return-pipes J J^1 in the usual manner, except that in the system herein described, each radiator has a 85 separate return-pipe which does not directly enter the boiler, but discharges into a condensation-receiver K which may be common to all the return-pipes of the system. 90

Each return-pipe J J^1 is provided with a check-valve L L^1 just before it reaches the condensation-receiver K which prevents a back flow of water and air from said receiver, such as might be caused by the shutting off 95 of a single radiator of the system and the formation of a partial vacuum in said radiator and its return-pipe. The check-valve also obviates the necessity of shutting the corresponding return-valve g^9 g^{10} which therefore 100 is rendered unnecessary except in case of accident to the corresponding return-pipe or where necessity arises for repairs or changes in said pipe or in the corresponding radiator. In case of accident to the return-pipe of any 105 radiator, the return-valve of said radiator may be closed and the feed-valve g^{12} g^{13} g^{14} left open and the radiator will continue to do

its work, because the water of condensation will then return by the supply-pipe and drip-pipe to the boiler as in a "one-pipe" system.

The condensation-receiver K is tubular and 5 inclined, its lower end being attached to the upper end of a stand-pipe k^1 which enters the boiler below the water-line and its upper end is provided with an automatic air-valve k^2 which should be raised a few inches above 10 the check-valves L L^1 all of which are arranged at the same level. All of the return-pipes J J^1 are placed at the same inclination and on a level with each other at their lower ends in order that the draft or flow of water 15 from all the radiators may be equal and that the circulation may be uniform in all the radiators of the system.

For convenience of illustration the pipe J^2 is not shown in connection with the condensation-receiver in the enlarged view of Fig. 3, 20 but is shown in Fig. 2.

None of the return-pipes should discharge directly into the stand-pipe k^1 , but upon the inclined bottom of the receiver, because the 25 dropping of the water down said stand-pipe k^1 would prevent the air from rising when the boiler is first started or when there is no steam pressure.

The condensation-receiver K may be more 30 conveniently made in separate sections k^3 k^4 so that any desired number of such sections may be secured to each other as shown in Fig. 3, every section being provided at its upper end with a conical enlargement or seat 35 k^5 k^6 adapted to receive and fit the conical lower end k^7 k^8 of the section next above and the end-portions of the sections being provided with ears k^9 k^{10} which may be connected by bolts k^{11} k^{12} and nuts k^{13} k^{14} in an obvious 40 manner.

The uppermost section k^{15} of the condensation-receiver is merely a reducer to which the automatic air-valve k^2 is connected by means of the pipe k^{16} in an obvious manner. 45 Making the condensation-receiver in sections permits the return-pipes to be connected to the sections before said sections are joined together.

The radiator G^2 is represented as connected with the branch supply-pipe H^1 , and with a separate drip-pipe H^1 which discharges into the stand-pipe i^3 above the water line of the boiler A, said stand-pipe i^3 entering said boiler below the water-line and having 50 a part i^4 above the lower end of said drip-pipe which serves as an air-chamber and is provided with an automatic air-valve i^5 , all 55 these parts being of the same construction and for the same purpose as the similarly 60 named parts previously described.

Both the main supply-pipe H and the branch supply-pipe H^1 lead out of the same vertical stand-pipe h , being connected thereto by short pipes h^2 h^3 , each inclined at an angle of about forty-five degrees to said stand-pipe to facilitate the passage of the steam.

The parts and connections of the radiator G^2 are similar to those of the radiator G^1 marked by corresponding letters of reference 70 with indices less by one.

The return-pipe J^2 also has a check-valve L^2 and leads into the condensation-receiver K just as the pipes J and J^1 are above described as doing.

Placing the air-valves of the drip-pipe above the lowest end of the supply-pipe allows the escape of the air from said supply-pipe through the drip-pipe and prevents "pounding" and obstruction of circulation 80 in both of said pipes.

Arranging an automatic air-valve on the condensation receiver above the highest point of said receiver allows air to escape from the return-pipe and prevents "pounding" in the radiators and return-pipes.

I claim as my invention:

1. The combination of a boiler, a plurality of radiators connected therewith, a separate, downwardly inclined return-pipe for each 90 radiator, a check-valve in each return-pipe, an inclined condensation-receiver, into which all said return-pipes enter, said condensation-receiver being arranged above the water-line of said boiler and being connected with said boiler below said water-line, an air-chamber leading out of the upper end of the condensation-receiver, and an automatic air-valve leading out of said air-chamber and arranged above all said check-valves.

2. The combination of a boiler, a plurality of radiators connected therewith, a separate return-pipe for each radiator, all said return-pipes having an equal downward inclination, a check-valve in each return-pipe, all said check-valves being at the same level, an inclined condensation-receiver, into which all said return-pipes enter, said receiver being arranged above the water-line of said boiler and connected with said boiler below 110 said water-line, and an air-chamber leading out of said receiver and having an automatic air-valve arranged above all said check-valves.

In testimony whereof, I have affixed my 115 signature, in presence of two witnesses.

MARSHALL F. SMITH.
